UNITED STATES PATENT OFFICE.

GEORGE ASHLEY WILSON, OF LIVERPOOL, COUNTY OF LANCASTER,
ENGLAND.

INKING MECHANISM FOR PRINTING-MACHINES.

SPECIFICATION forming part of Letters Patent No. 298,147, dated May 6, 1884.
Application filed August 23, 1883. (No model.)

To all whom it may concern:

Be it known that I, GEORGE ASHLEY WILSON, a subject of the Queen of Great Britain, residing at Liverpool, in the county of Lancaster, England, have invented a new and useful Improvement in Inking Mechanism for Printing-Machines, of which the following is a specification.

My invention relates to apparatus for carrying ink from the inking-trough roller or ink ductor-cylinder to the ink-distributing drum or table of printing-machines.

The main objects are to provide mechanism or apparatus in which the motions of the carrying-roller which takes ink from the trough-roller or ductor-cylinder and gives it to the drum or table may be adjusted and regulated with greater precision than heretofore, so that the requisite quantity of ink, and neither more nor less, may be deposited on the drum or table, and to allow of the whole or parts of the apparatus being easily disengaged or thrown out of gear, so that they may be separately adjusted to their work. I attain these objects by the mechanism illustrated in the accompanying sheets of drawings, where-

Figures 1 and 2 are views of the opposite ends of the machine embodying my invention, the distributing-drum 26 having been omitted in Fig. 2. Fig. 3 is a side elevation, parts being broken away, and the distributing-drum, carrying-roller, and bell-crank lever by which the latter is actuated having been omitted for sake of clearness. Fig. 4 is a horizontal section through the driving-wheel 6 and its clutch mechanism. Fig. 5 is a similar section through the eccentric 14 and its connections. Fig. 6 is an elevation of collar 7.

Like figures refer to like parts wherever they occur.

1 is part of the frame-work of the printing-machine; 2, ink-trough, of usual construction, secured to the frame in any suitable manner, such as by bolts and nuts; 3, ductor-cylinder carried by shaft 4 and working in bearings 5; 6, driving-wheel fitted to work freely on the shaft 4 and held in position by the collars 7, 8, secured to the said shaft by set-screws 9. The collar 7 has inclined curved grooves 10 cut therein, into which takes a pin, 11, fitting

into a recess in the boss of the wheel 6. 12 is a helical spring fitting in the before-mentioned recesses behind the pin 11, so as to keep it pressed against the face of the collar 7. More than one pin may be used, and the number of 55 slots 10 may be varied. This construction enables me to change the relation of the cylinder 3 to the driving mechanism and to adjust it with relation to the carrying-roll 25 without disturbing the driving mechanism. 60

In practice I find two slots and one pin answer well when the wheel and collars are cast-iron and the pin steel. The above construction allows of the inking apparatus being turned forward for adjustment or otherwise without 65 moving the driving-wheel 6 or the rest of the machinery, as the pin 11 travels along the slots 10, and is gradually pushed back by the inclined surface. When forward motion is given to the driving-wheel, the pin moves into the deep 70 end of one of the slots and carries round the collar 7, and with it the inking apparatus. Collars 13, fixed to the shaft 4, retain between them the loose eccentric 14. The loose eccentric 14 is formed or provided with a projecting piece, 15, adapted to fit against a projecting piece, 16, on the boss of the hand-wheel 17. The hand-wheel 17 is free to slide to and fro on the shaft 4 within the limits allowed by the fixed collars 13 and 18, so that the projections 15 and 16 may be caused to engage and disengage. 19 is a key fitted securely to the shaft 4 and freely within a slot in boss of the hand-wheel 17; 20, eccentric-strap, from which extends an arm, 27, that is connected with 85 bell-crank lever 23, and imparts motion thereto; 21, pin; 22, slot in bell-crank lever 23, by which means the connection between the eccentric and bell-crank lever may be adjusted to vary the throw of the bell-crank lever and 90 the travel of carrying-roller 25; 24, fulcrum pin or bearing for lever 23; 25, carrying-roller in bearings on the upper end of the lever 23; 26, distributing drum or table. When the hand-wheel is in the position shown in the 95 drawings, motion may be given to the ductor-cylinder 3 without imparting motion to the eccentric 14 and carrying-roller 25. When the hand-wheel is moved close against the eccentric, so that the projecting pieces 15 and 100

16 are in contact, any motion imparted to the ductor-cylinder 3 will be imparted through the boss of the hand-wheel 17 to the eccentric 14, and thence to the carrying-roller 25. The 5 said hand-wheel serves as means for giving motion to the inking mechanism independently of the driving-wheel 6, so that the inking mechanism may be set in motion, the rest of the machine being at rest, for the purpose of 10 judging whether any and what adjustment of the relative motions and positions of the parts is required. The extent of vibrating motion of the carrying-roller is regulated by the position of the pin 21 in the slot 22. A nut or 15 set-screw is used to secure the pin in the desired position.

The distributing drum or table, which may be flat, cylindrical, or of other suitable shape and stationary or movable, is constructed in 20 any usual or desired manner.

I claim—

1. In inking apparatus for rotary printing mechanism, the combination, with the ductor-shaft, of an eccentric loose upon the shaft and 25 provided with a projecting pin or clutch-piece, a sliding hand-wheel splined to the shaft and

provided with a pin or clutch-piece, a carrying-roller, and interposed mechanism, substantially as described, for actuating the carrying-roller from the eccentric of the ductor-shaft, substantially as and for the purposes 30 specified.

2. In inking apparatus for rotary printing-machines, the combination, with the ductor-shaft, of an eccentric and devices, substantially 35 as described, for causing the same to move with the shaft, an eccentric-strap having an arm provided with a pin, 21, an elbow-lever having its fulcrum at the angle and one arm slotted for the adjustment of the pin 21, and 40 a carrying-roll journaled on the vertical arm of the elbow-lever, substantially as and for the purposes specified.

3. The combination of the shaft 4, driving-wheel 6, and disengaging mechanism with the 45 hand-wheel 17 and clutch mechanism, and the eccentric 14 and carrying-roller and connections, substantially as set forth.

GEORGE ASHLEY WILSON.
